UNITED STATES PATENT OFFICE.

ERLE KING BAKER, OF CHICAGO, ILLINOIS, ASSIGNOR TO UNIVERSAL RIM COMPANY, OF CHICAGO, ILLINOIS, A CORPORATION OF ILLINOIS.

TRANSPLIT RIM.

Application filed August 14, 1916. Serial No. 114,798.

To all whom it may concern:

Be it known that I, ERLE KING BAKER, a citizen of the United States, residing at Chicago, Cook County, Illinois, have invented certain new and useful Improvements in Transsplit Rims, of which the following is a specification.

My invention relates to improvements in demountable rims for automobiles, and has 10 special reference to improvements in demountable rims which are adapted to carry pneumatic tires.

In dealing with demountable rims, it is necessary that the same shall be formed for 15 easy assembly with the tire and shall be easy to detach therefrom. In the case of rims of the clincher type it is desirable, and in the case of rims of the straight-side it is essential, that the rims shall be transsplit, if 20 of the integrally flanged form. By "transsplit" I mean transversely cut across to form rim ends which may be helically separated, as required to make the rim easy to manipulate. When a rim has been transsplit it 25 becomes necessary to provide means for connecting the ends of the rim at times when it is on the wheel, and it is also desirable that the rim-end connecting means shall be adapted to always hold the rim ends in 30 alignment and also prevent the relative displacement thereof in radial directions.

The object of my invention is to simplify 35 the construction of transsplit demountable rims, and to improve the action thereof.

The general nature and principles of my 40 invention, and also the details of the best embodiment thereof that I have thus far devised, will be readily understood on reference to the drawings which form part of this specification, and are particularly 45 pointed out in the appended claims.

In said drawings, Fig. 1 is a side elevation 50 of a fully equipped motor vehicle wheel embodying my invention; Fig. 2 is a full size cross section on the line 2-2 of Fig. 1;—Fig. 3 is a full size cross section on the line 3-3 of Fig. 1;—Fig. 4 is a detail section on the line 4-4 of Fig. 2, but reduced in size;—Fig. 5 is a detail of the 55 shouldered felly band from the position of the arrow in Fig. 2;—Fig. 6 is a sectional detail on the middle plane of the wheel, showing the appearance of the parts at the split of the rim, as on the line 6-6 of Fig. 60 7;—Fig. 7 is a plan view from beneath, of

the parts shown in Fig. 6 on the irregular line 7-7 of Fig. 6;—Fig. 8 is a perspective view depicting the interlocking and driving plates or projections on the inner periphery of the rim at the split;—Fig. 9 is a sectional view from the position of line 9-9 of Fig. 7, detailing the manner of attaching the driving plates to the demountable rim;—Fig. 10 is a modification thereof;—Fig. 11 is a plan view of the portion of the felly 65 band and felly which contain the valve stem and driver holes;—Fig. 12 illustrates a modification of my invention in which the interlocking projections are formed from the body of the rim instead of upon separate 70 plates, being a section on the line 12-12 of Fig. 13;—Fig. 13 is a view of the inner periphery of the demountable rim at the split, and on the line 13-13 of Fig. 12;—and, Fig. 14 is a perspective detail of the 75 rim ends.

In the drawings, 1 represents the wheel hub; 2 the spokes; 3 the felly; and, 4 the felly band or fixed rim. This band is mainly cylindrical in form, but is provided with 80 a conical back flange, 5, which overhangs the inner side of the felly; that is, the side toward the vehicle. In the felly, beneath the felly band, I provide a number of clamping bolts, 6. The heads, 7, of these bolts 85 abut against shoulders, 8, formed therefor on the body of the felly band. These shoulders are formed by shearing the band and pushing up the portions, 5', of the back flange, as well shown in Figs. 2 and 5. The outer ends of the bolts are threaded and are provided with nuts, 8, and small rectangular, ribbed washers, or pressure lugs 9. In each case the nut has a sleeve-like boss, 8', 90 which is swedged loosely within the washer, 9. As shown, the clamping bolts and lugs are spaced about the felly, and, as herein-after explained, they act upon the demountable rim to force the same firmly 95 upon the conical back flange, 5.

The parts marked 10 are centering projections or ribs, on the periphery of the felly band, preferably adjacent the back flange. I prefer that these ribs shall be pressed-up 100 from the body of the felly band. There may be as many thereof as there are bolts, and they are preferably placed between the bolt spacings, though they may be otherwise located on the face of the felly band. Their tops are, so to speak, on a level with 105 110

the bottom of the inclined surface presented by the back-flange, 5. The demountable rim, with which this invention is concerned, is of the kind which is characterized by a 5 generally cylindrical form, and by integral tire-holding flanges. Referring again to the drawings, R represents the demountable rim, and r' the integral flanges thereof. It will be noted that the demountable rim is 10 of greater diameter than the fixed rim on the wheel, so that an annular space, 11, remains between the two rims.

The centering projections, 10, before referred to, are preferably of substantially the 15 same height as the space and serve to guide the demountable rim against the back-flange, 5, and cause it to be concentric with the wheel, in a plane perpendicular to the axis of the wheel.

20 The demountable rim is supported by the back flange of the fixed rim in the manner shown in Fig. 2, and is firmly held in that position by the pressure lugs, 9, acting through the integral, sheared-and-pressed 25 down peripheral projections, r'' , of the rim. There are as many of these projections as there are clamping bolts.

Now that the construction and relation of the wheel and the demountable rim have 30 been explained, I shall point out the peculiar features which constitute the special subject-matter of this application.

When stretchable bead tires are employed, such as the ordinary standard clincher tire, 35 the integral flanges of the demountable rim may be of the clincher type, and the rim may be of the endless type. This is because the beads of the tire may be stretched over the flanges and thus lodged on the rim. 40 But when either straight-side or clincher tires having non-stretchable base beads are to be employed, the integral flanges of the rim prevent the putting of the tire and rim together, unless the rim is in some manner 45 adapted to be contracted to the extent necessary to pass the base beads. Such straight-side tires, T, are shown in these drawings. It should be understood that the base beads or flanges r' , thereof are of the inextensible 50 or non-stretchable kind. To obviate the difficulty mentioned, I transplit the rim, i. e., cut it across at one point in its circumference, so that its ends may be passed by one another as required to contract and expand the rim 55 to the extent necessary for easy assemblage with the tire. I prefer that the transplit or cross cut shall be of the diagonal kind, which characterizes my earlier patented rims, to the end that the rim-ends may be 60 transversely and helically separated. The action of such a transplit rim is now so well understood that I deem it unnecessary to particularly describe the same.

65 Referring now to Fig. 7, it will be seen that I cut the demountable rim upon a gen-

erally diagonal line, i. e., a line beginning at a point on one flange thereof and extending to a circumferentially advanced point on the other flange. This diagonal cut comprises a major diagonal, 12, and a minor 70 diagonal, 13. The latter extends only a little way through the side flange of the rim and does not materially interfere with the transverse opening or separation of the rim ends. This opening or separation is well depicted in Fig. 8. I call attention to the fact that the major diagonal, 12, is formed on an angle of twenty-five to thirty degrees, whereas, the minor diagonal is an angle of approximately two degrees. By splitting the 80 rim in this way I provide it with rim-ends which normally align one another, it being understood that either the resilience of the rim or the pressure of the tire thereon presses the rim ends firmly together. 85

In addition to the described provision for the alignment of the rim ends, I also provide means which prevent the radial separation of the rim ends; and I accomplish this effect without making it necessary to circumferentially separate the rim ends before beginning to laterally separate them. This feature is of great importance, inasmuch as the tolerance between the rim and the tire often is no greater than one-sixteenth of an 95 inch.

The parts to which I have just referred are well depicted in Figs. 6 to 8, and comprise two plates, 14 and 15, riveted or otherwise secured to respective rim ends, R^1 and R^2 . The plate, 15, is provided with a tongue or extending part, 16, which obviously underlaps the other end of the rim, when the rim ends abut upon the line 12—13. This tongue is sufficient to prevent radial separation of the rim ends in one direction. To prevent separation in the other direction, I provide an underlying lug, 17, on the plate, 14. Between this lug and the rim end is a pocket, 18, deep enough to receive a part of 105 the tongue, 16. As the rim ends are put together in the act of aligning them, the tongue, 16, slips into the pocket, 18, and thus the radial interlockment of the rim ends is completed. The position and depth of the 110 pocket, 18, are such that the inner end, 16, of the tongue, is liberated from the outer end of the lug, 17, at the moment of the lateral disengagement of the rim end parts which comprise the line, 13, or even before 115 that occurs. Being thus liberated, the lug, 16, may be forced down with the rim end, R^2 , as required for the passage of the opposite flange of the rim beneath the bead of the tire. This action will be understood by 120 those who are skilled in the art.

I prefer that the valve stem hole, V, of the rim shall be located close to the split, both for convenience in manipulating the rim and to the end that the valve stem 130

spreader, V' , may overlap the split, as shown in Fig. 6. The valve-stem hole is placed in the plate or plug, 14, adjacent to the raised lug, 17.

5 The plates 14 and 15 perform still other functions. I take advantage thereof to employ them as driving studs for the rim. Preferably, the felly band, 4 (see Figs. 6, 7, and 11) is provided with struck-up portions, 19, 19, positioned to engage the respective ends of the plates, 14, 15. And to ensure strong engagement, I provide the plates with turned-down under-lugs, 20, which engage the struck-up parts, 19, as best shown 10 in Fig. 6. It will be clear that as there is one driving stud or connection on each rim end, and that as both thereof engage the felly-band, the rim ends are firmly connected when positioned on the wheel. To accommodate the inwardly or downwardly turned lugs, 20, I perforate the felly band, 4, making one short perforation, 21, at one end; and a long perforation, 22, at the other. The long perforation accommodates the valve 15 stem hole, V'' , in the felly, and also makes room for the lug, 17, on the plate, 14, (see Figs. 6 and 7).

Still another function is performed by the plates, 14, 15. On referring to Figs. 3 and 30 8, it will be noted that the outer ends or edges of the two plates, 14, 15, extend beyond the outer edge, 4^a , of the felly band, just as do the shoulders of the projections, r'' . This being the case, the edges of the 35 plates, 14, 15, are availed of as an abutment for one of the pressure lugs, 9. This relation is shown by dotted lines in Figs. 6 and 7, and also appears in Fig. 1.

The arrangement of the clamping device 40 at this point places the bolts in the position shown in Fig. 11, and this in turn explains the forms of the slots, 21 and 22, in the felly band. In other words, I use two slots at that point in order to leave the solid bridge, 45 23, between them above the bolt, otherwise the wood would break out where exposed in the slot.

I prefer that the plates, 14, 15, shall be riveted rather than welded to the rim ends, 50 and to provide connections stronger than ordinary rivets, I form either the plates or the rim ends in the manner shown in Figs. 9 and 10. In Fig. 9 the rim, R , is shown provided with punched-down bosses, r^x , which pass 55 through holes in the plate 14 or 15. Then the rivets, 24, are passed through and clinched or riveted within the holes in the bosses, r^x , thus expanding the latter. In this manner the plates are very firmly bound on 60 the rim ends, and while in fact secured by the rivets, they exert their force against the integral bosses on the rim ends. In Fig. 10, the relation of the parts is shown reversed, the boss, w , being formed on the 65 plate, 14 or 15, to the same effect.

It will now be understood that in placing the rim in a tire the valve stem of the tire is first put through the hole, V , and the beads of the tire are seated between the flanges of the rim at that point. The operator then 70 presses the tire between the flanges progressively from that point onward, to the other end of the rim, which other end is meantime helically separated in the usual manner. At the end, the corner, A, of the 75 rim is presented to the corner, B, (see Fig. 7) and the last end of the rim is then forced into alignment with the first end, i. e., the end containing the valve stem hole, V . This action causes the lodgment of the tongue, 80 16, in the pocket, 18, and completes the locking of the rim ends.

I take it, that one who is skilled in the art will immediately understand that the interlocking tongue and lug, instead of being 85 formed on separate plates, as in Fig. 8, may readily be formed from, and integral with, the ends of the rim. To make this clear, I have depicted such a construction in Figs. 12 and 14.

As the first step, I form the two ends of the rim, R^4 , and R^5 , of the rim so that they shall interfit upon relatively diagonal self-aligning angles, 12^x and 13^x , as before described. But in doing this I form a tongue, 90 16^x , on the end, R^4 , and press the same into the form shown in Fig. 14. In this condition the outer side, 16^y , of the tongue is made substantially flush with the inner periphery of the rim. I also cut and depress the 95 end portion of the part, R^5 , to form the integral lug, 17^x , which is of a depth to allow the entrance of the tongue, 16^x , between the rim and the lug, 17^x , as well shown in Figs. 12 and 13. Referring now to Fig. 13, it will 100 be seen that the pocket-forming lug or embossment, 17^x , is shorter than the tongue, 16^x . In consequence, when a portion of the tongue, 16^x , is engaged with the part, 17^x , the remainder of the tongue laps upon the 110 undisturbed portion, R^x , of the end, R^5 . Thus the tongue (and end R^4) is held against radial movement in either direction with respect to the end, R^5 .

As shown, the valve stem hole, V^x , is 115 placed close to the part, 17^x , and the operation of the rim is quite as convenient as in the case of the diagonally split and radial interlocked rim shown in Figs. 1 to 8.

In the case of the integrally interlocked 120 rim, I employ driving studs which are separate from the interlocking parts. The construction is well depicted in Figs. 12 and 13, where it will be seen that the rim ends are punched and provided with spacing bosses, 125 25, preferably at equal distances from the valve stem, V^x . In these holes I secure the studs, 26, which project inward beyond the bosses and engage in holes, 27, provided in the felly band or fixed rim, 4^x .

When the annular space, 11^x, between the rims is as small as depicted in Fig. 12, it is necessary to punch a hole, 28, in the felly band to accommodate the pocket forming lug, 17^x, of the demountable rim.

With this construction it is unnecessary to provide a clamping bolt adjacent to the split of the rim, but if desired the axial pressure device may be arranged at that point.

10 Having thus described my invention, I claim as new and desire to secure by Letters Patent:—

A transversely split demountable tire-carrying rim, presenting a substantially cylind-

rical base and transplit on a diagonal line, 15 in combination with a tongue applied to the inner periphery of the rim at one rim end and a tongue receiving pocket portion provided on the inner periphery of the other rim end, in such positions that when interlocked the tongue is retained between the rim base and the pocket receiving portion on the rim end opposed to that which carries the tongue.

In testimony whereof, I have hereunto set 25 my hand this 9th day of August, 1916.

ERLE KING BAKER.
